WILLIAM T. PLUM, JR., OF OAKHURST, NEW JERSEY

SOUND APPARATUS

Application, filed January 6, 1930. Serial No. 418,727.

This invention is directed to an improved method and apparatus for obtaining certain desired results in sound, and has for one of its objects the provision of a method and apparatus whereby sound waves emanating from a central source may be selectively intensified and/or damped as desired, thereby effecting an increase in intensity of certain sound and/or a decrease in others whereby in an enclosure, such as an auditorium, for example, the sounds from a main source, such as a stage, may be heard with the correct and desired intensity throughout the entire enclosure.

It will be obvious from the description which follows that a great variety of effects may be produced by my improved method and apparatus, but in order that any invention may be clearly understood I shall confine the description thereof to a method and apparatus as applied in connection with sound production within an enclosure or chamber, such as an auditorium.

In such enclosure it has been impossible prior to my invention to obtain correct results throughout the auditorium so far as proper reception of the sounds from a central source, such as a stage, are concerned due to echo effects, absorption effects and directional effects which are inherent in the structure of the enclosure.

Various means have been tried to overcome these effects mainly directed, however, to the placing of some sound absorbing medium at those places or zones where the sound is otherwise intensified, or sound reflecting mediums at those places or zones where the sound is otherwise absorbed or damped.

My invention goes far beyond this, however, in that the sound absorbing and/or sound reflecting mediums heretofore employed absorb or reflect, as the case may be, to a certain degree all sounds coming in contact with them so that what is gained in absorbing or reflecting certain sounds is lost by absorbing or reflecting others as well. Difficulty has been experienced with these prior devices with directional effects which are also objectionable.

In the practice of my invention I delib-

erately select the sound waves which are to be damped or the amplitudes of which are to be increased without, however, altering when my invention is in operation the amplitude of the remaining waves. In this way true effects may be obtained throughout the entire enclosure or auditorium.

More specifically, my invention consists in the employment of sound intensifying means and/or sound damping means, the character and location of these means being preselected and dependent upon the results desired.

For example, in an auditorium where owing to the construction thereof echo effects are pronounced, it has been customary, as above pointed out, to employ sound absorbing mediums, such as draperies, nets or other means at that location. As also pointed out above these mediums are not satisfactory in that they absorb to a detrimental degree all sound striking them, being most absorbent of course to those sounds having frequencies which are most readily damped by the medium employed. This characteristic will naturally vary depending upon the type of absorbing mediums employed.

As distinguished from such an expediency I place a damping means at such a location which could, for example, take the form of a tuned resonator tube, this tube being designed so as to be responsive only to the wave to be damped. It will also be placed in a predetermined location with respect not only to the central sound source but also with respect to the sound reflecting source, being so located as to be in phase with the original sound wave but out of phase with the reflected sound wave. As a consequence the resonator will be caused to vibrate by the original sound wave being in phase with it, thereby to damp the reflected wave with which it is out of phase.

In those locations where the sound is naturally absorbed owing to the construction of the enclosure I propose to place sound intensifying means. This means may take the form of a resonator tube which is tuned and responsive only to those sound waves which are to be intensified and will be located, as before, in phase with the original sound and

at the same time in phase with the sound waves of the same theoretical frequency reflected by the sound absorbing area under consideration.

5 At other locations in the auditorium, for example, beneath the balconies, difficulty has been experienced heretofore in absorption of sounds by the balcony structure so that sounds are barely audible at that part of 10 the auditorium lying beneath the rear of the balcony. This balcony structure of course absorbs sound waves of all frequencies to some degree and in this connection I propose to place a bank of tuned resonator 15 tubes at or adjacent the edge of the balcony, these tubes being so located with respect to the central sound source as to be in phase with the waves emanating therefrom. In this way I obtain a reinforcement of all sounds reaching 20 the balcony and a resultant increase in intensity of all sounds traveling to the back of the auditorium beneath the balcony.

In the accompanying drawings wherein I have illustrated my invention diagrammatically Fig. 1 is a plan view and Fig. 2 a section on the line 2—2 of Fig. 1. A designates an enclosure such as an auditorium in which sounds are to be produced from a central sound source or main sound source shown 30 at B and which may be in the nature of loud speakers. This central or main sound source is located on the stage C.

D designates a balcony, while E designates a column or post along one wall of the auditorium, and F designates a room along another wall. The balcony D, post or column E and room F are shown merely as illustrative of sound absorbing means and sound reflecting means which effect the proper distribution of sound from the main source B throughout the enclosure. As mentioned above in the general discussion of my invention, the effect of the balcony D is to absorb to a detrimental degree sounds produced by 40 the main or central source B so as to render it extremely difficult for these sounds to be audible on the lower floor of the auditorium beneath the balcony, particularly at the rear of the balcony. To overcome this defect I 45 place at or adjacent the front edge of the balcony a series of resonator tubes designated G, as many as found necessary. These resonators are tuned, each resonator having its own natural period of vibration and their effect is to intensify the sound waves having the 50 same frequency as the natural period of vibration of the tubes.

It is to be understood that each tube will 55 be located in phase with the waves corresponding in frequency to the natural period of vibration of the tube. It will be appreciated that the effect of a bank of these tubes will be to intensify the sounds emanating from the 60 sound source B with a resultant increase in

the intensity of the sounds traveling into the space beneath the balcony.

The post or column E has been shown as an example of another type of sound absorbing medium and in order that the effects resulting from the absorption of sounds by this column may be overcome I place in proximity to the column a tuned tube or tubes H, this tube being tuned and designed with reference to the frequency of the waves which are absorbed by column E, and the tube is so located with respect to the column E as to be in phase with the wave or waves which are most readily absorbed by the column, and at the same time in phase with the waves which theoretically are reflected by the column. In this way the absorptive effect of the column is effectually overcome.

The room F has been shown merely as illustrative of a construction tending to produce echo or reflective effects in the auditorium and in order that these effects may be overcome I place adjacent this room one or more tuned resonators I; each resonator will be so located as to be in phase with the wave or waves to which it is responsive and out of phase with a wave of the same frequency reflected from the wall J which is along one side of the room F. In this way the tube or tubes I will be set into vibration but out of phase with the waves reflected by the wall J to damp the same and thus eliminate the reflection or echo effect.

It will be understood that my invention may be practiced in a variety of ways without departing from the spirit and scope thereof, and that the drawing is merely illustrative and not definitive.

What I claim is:—

1. In sound production the method of reducing sound absorbing effects which comprises placing tuned resonators in proximity to the sound absorbing medium, said resonators being so placed as to be in phase with sound waves corresponding in frequency to the frequency for which they are designed and in phase with waves of the same frequency reflected from the absorbing medium.

2. In the production of sound within a chamber the method of reducing echo effects which method comprises placing tuned resonators in proximity to the structure producing the echo, said resonators being in phase with sound waves of the same frequency as the natural period of the resonators emanating from a sound source and out of phase with waves of the same frequency reflected from the echo producing structure.

3. In the production of sound within an auditorium the method of improving the distribution of sound therein which comprises the selective placing of resonators tuned to predetermined frequencies in such relation to the sound source as to be in phase with the sound waves having frequencies correspond-

ing to the natural period of vibration of the resonators, and in such position with respect to the auditorium structure that some of said resonators will be in phase and others out of phase with sound waves reflected by certain preselected areas of the auditorium structure, so that in some instances a reinforcement of the sound waves and in others a damping of the sound waves will be effected.

13 4. In the production of sound the method which comprises the placement of a plurality of tuned resonators responsive to a sound source in operative relation with the sound source at predetermined distances therefrom to neutralize by phase difference the sound waves that are reflected from certain surfaces in the path of the sounds from the sound source.

15 5. In the production of sound the method which comprises placing a plurality of tuned resonators responsive to a sound source in operative relation with the sound source and at predetermined distances therefrom to reinforce by similar phase coincidence the waves that are reflected from certain surfaces in the path of sounds from the source.

20 6. In the production of sound the method which comprises placing a plurality of tuned resonators of predetermined frequency responsive in operative relation with the sound source at predetermined distances therefrom, thereby to place certain other frequencies of the waves from the source by interference of waves from the resonators and waves from 25 the sound source.

30 7. In the production of sound the method which comprises placing a predetermined number of tuned resonators responsive to sounds from a sound source in operative relation to the sound source and at predetermined distances therefrom, said resonators being also located at predetermined distances with respect to reflection of sounds from said source from disturbing areas in the path of 40 45 the sound wave emanating from the sound source, thereby to reinforce the waves reflected from said disturbing areas by coincidence in phase of the resonators and the reflected waves.

50 8. In the production of sound the method which comprises placing a plurality of tuned resonators in operative relation to and at predetermined distances from a sound source and also at predetermined distances with respect to sounds reflected from disturbing areas located in the path of sound waves emanating from the sound source, thereby to neutralize the waves reflected from the disturbing areas by differences in phase of the 55 60 resonators and the reflected waves.

65 9. In sound production the combination of a sound source, an absorbing area in the path of sound waves emanating from said source, and resonators intermediate the sound source and absorbing area and tuned to and in phase

with the sound waves emanating from said source so as to reinforce the initial waves from the sound source whereby the final waves at the absorbing area have the same amplitude as previous to their contact with the absorbing area.

This specification signed this 3rd day of January, 1930.
